UNITED STATES PATENT OFFICE.

JOHN N. DAVIS, OF DAYTON, OHIO, ASSIGNOR TO THE WESTON PAPER AND MANUFACTURING COMPANY, OF SAME PLACE.

PAPER VESSEL.

SPECIFICATION forming part of Letters Patent No. 656,439, dated August 21, 1900.

Application filed June 11, 1900. Serial No. 19,813. (No model.)

To all whom it may concern:

Be it known that I, JOHN N. DAVIS, a citizen of the United States, residing at Dayton, in the county of Montgomery and State of Ohio, have invented certain new and useful Improvements in Paper Vessels, of which the following is a full, clear, and exact description, reference being had to the accompanying drawings, forming part of this specification.

10 My invention relates to paper vessels designed for liquids, oysters, berries, ice cream, and the like; and the special object of the invention is to provide a vessel which can be filled and handled with liquid material with-
15 out leaking or spilling and which when closed shall be slop-proof; second, to so fold the top that a very cheap and effective fastening may be used to lock the top shut; third, to provide such thick and heavy folds for the sides of
20 the top that the top will fold down naturally and easily into the proper position, the side folds forming a break or folding edge for the top covers.

In the drawings, Figure 1 is a plan view of
25 the blank from which the vessel is folded. Fig. 2 is a perspective view of the vessel closed. Fig. 3 is a side elevation of the vessel open, with part of the side wall cut away to show the interior fold. Fig. 4 is a detail central
30 vertical section of the upper side edge of the vessel when closed, taken on the lines 4-4 of Fig. 2.

The body of the vessel is made up of bottom A, sides B B, ends C C, with folds D and
35 E between the sides and ends. The sides are provided with side extensions F F and the ends with end extensions G G, while between these side and end extensions are the extension folds H and I. The blank is properly
40 creased with fold-lines between the various parts, as shown in the drawings in Fig. 1, and in addition the corners between the side extensions F F and the extension folds H H are creased with the diagonal score-lines a b.
45 The blank is then ready for folding, and the sides and ends are brought into upright position and the corner folds D E folded over on the outside, so as to overlap, as shown in Figs. 2 and 3. In this position the side and
50 end extensions F and G and the extension folds H and I will stand up in vertical posi-

tion, extending above the top line f of the vessel, the end extensions G G forming a single continuous wall with the ends C C, while the side extensions F F form a single continuous wall on the inside with the sides B B. The triangular folds at the corners between the side extensions F F and the extension folds H H are then folded outwardly on the score-lines a b, as shown in Fig. 3, and we then have a heavy triangular fold at the upper portion of the sides of the vessel. The ends of the bail L are then inserted through the folds D E at the points d, so as not to pierce the sides B B, and strips of tin M are inserted through the overlapping extension folds H I and the side extensions F F at the points e e. These strips of tin M are clenched on the inside and folded down on the outside flat with the extension folds, as shown in Fig. 3. In this way the various overlapping side folds are securely fastened, leaving the sides and ends of the vessel to the top line f of the pail smooth and intact and without any opening of any kind through which the liquid being poured into the vessel can leak out or escape, and in addition to this there will be five thicknesses of the paper at the sides, which will very materially assist in folding the top in the manner now to be described. The vessel having been filled with the desired contents, the sides are folded in horizontally, bringing their upper edges together and causing the end extensions G G to fold down on top on the score-lines c c. These end extensions G G are formed of such a width that they will overlap, and the folding down of the sides will leave the strips of tin M M extending out horizontally, as shown by the dotted line g in Fig. 4. The strips of tin are then bent up over the overlapping edges of the end extensions G G, as shown at h h in Fig. 2, and the paper vessel is securely closed and locked.

The special features of importance in my improved paper vessel consist in the heavy triangular folds that are formed on the sides and in the folding down of these sides, so as to bring the end extensions together and cause them to slightly overlap, the weight of material in the sides rendering it a very simple and easy operation to thus close the ves-

sel. In addition to this the tin strips which lock the side folds together are thus brought by the folding in of the sides in a perfectly horizontal position, to be instantly folded 5 over the overlapping edges of the end extensions to lock the cover into place. In this way an absolutely slop-proof vessel is obtained.

Having thus described my invention, what I claim, and desire to secure by Letters Patent, is—

1. A paper vessel, formed from a single blank of paper, having, bottom, sides and ends, side and end extensions with extension folds between them, the side extensions and 15 the adjacent extension folds being turned over at the corners outwardly, and the extension folds adjacent the end extensions folding inwardly on a diagonal line, said blank being folded into shape in the manner described, in which the side extension portions are folded inward with the end extensions overlapping on the outside, and means for locking together the overlapping end extensions to close the vessel, substantially as 25 shown and described.

2. A paper vessel, formed from a single blank of paper, having bottom, sides, and ends, with side folds between the sides and ends, side and end extensions with end extension folds between them, the side extensions 30 and the adjacent extension folds being turned over at the corners outwardly, and the extension folds adjacent to the end extensions folding inwardly on a diagonal line, said blank being folded into shape in the manner 35 described, in which the side extension portions are folded inward with the end extensions overlapping on the outside, and strips of tin passing through the side extension portions, clenched on the inside and lying flat 40 along the outside, whereby when the side extension portions are folded in and the end extensions overlap, the strips may be bent over the overlapping portion, to close the vessel, substantially as shown and described. 45

JOHN N. DAVIS.
